NUMERICAL ACCUMULATOR

Francis Galvin Wood, Los Angeles, Calif., assignor to Twentieth Century-Fox Film Corporation, Los Angeles, Calif., a corporation of New York

Application June 17, 1939, Serial No. 279,711

2 Claims. (Cl. 235—133)

This invention relates to tabulating machines and deals particularly with an improvement in an adding wheel in the numerical accumulator.

To those versed in tabulating work it is known that certain tabulating machines embody numerical adding wheels or, as they are sometimes termed, accumulators. These devices are used to show the sum which has been accumulated on the machine. However, in accumulating dollars and cents, for instance, the machine will often times show fractions which must in the final showing be corrected to the nearest whole number. For instance, if there is less than five-tenths, the final result should show the actual amount, but if there is five-tenths or more then the final result should show the next higher number. My invention has been conceived and designed and may be applied to a conventional numerical accumulator with slight modifications to render the wheel showing the fractions adjustable, so that when the adding wheel shows five-tenths or more the actual sum will read the next number above, and if it shows less than five-tenths the actual sum will show on the wheel. My invention has been so designed that the wheel showing the fractions may be so adjusted that it will operate in the conventional manner, or in the manner described above.

The modification required is simple and inexpensive and in actual practice results in eliminating a great deal of personal factor in operating such machines.

Other objects and advantages will become apparent as the description proceeds in conjunction with the drawing, in which:

Figure 1 is a view showing the face of an accumulator or, as previously termed herein, a numerical accumulator.

Figure 2 is a side view of an indicator wheel showing my invention incorporated therein.

Figure 3 is a front view of Figure 2, showing the change in the numerical indicia on the wheel.

Figure 4 is a cross sectional view, showing the changes brought about by my invention, and is taken on line 7—7 of Figure 5;

Figure 5 is an enlarged fragmentary view taken on line 8—8 of Figure 2; and

Figure 6 is a view similar to Figure 5, showing another way in which my invention may be applied.

Briefly stated, the invention amounts to changing the wheel which accumulates the fractions so that the carry over point, instead of being between 9 and 0, is between 4 and 5.

Since the invention is directed to those skilled

in the art and deals only with a single adding wheel, no details of operating or attendant mechanism associated with the wheel will be shown, it being deemed sufficient to show only that part of the accumulator which has been changed.

In Figure 1, I have shown a view of a conventional accumulator window. Here it will be noted that the numerals appear in a window 11 in the conventional manner. It is understood, of course, that each numeral appearing in the window 11 represents a separate indicator wheel in the accumulator and that said indicator wheels are driven by actuating mechanism in the ordinary manner. If, for instance, the accumulator is set to read dollars and cents with the decimal point indicated by the cross hatched partition and if it is required that the accumulator show only equal cents, it is obvious that under ordinary practice the machine should print \$50 instead of the \$.495 shown in the window. The conventional accumulator will not do this. In Figures 2, 3, 4 and 5, I have shown means whereby a conventional numerical wheel may be converted so that it will automatically raise one-half cent or more to actually read on the accumulator the next cent above. Here it will be noted that the unit comprises a wheel 22 having conventional numerals thereon and that the wheel is equipped with a gear 23 identical to a conventional wheel. The gear 23 is mounted upon the wheel 22 in the usual manner. Thus far, no changes have been made in the wheel from the usual construction. On the opposite side of the wheel, however, I have incorporated a change as follows: It will be noted that a carry over member 24 is mounted on the opposite side of the wheel and that this member has the usual conformation; that is, it carries the conventional synchronizing notches 25 and the conventional carry over finger 26. However, instead of fixedly mounting the carry over member 24 upon the wheel 22, I fix this member so that the relation of the finger 26 to the numerical indication on the face of the wheel may be changed. I do this by mounting a spacer block 27 between the member 24 and the wheel 22. It is to be understood that the spacer block 27 is drilled to carry the required number of holes to accommodate the pins 28 and the screws 29. Then, by cutting away the central portion of the carry over member 24 and replacing it with a plate 30 which has an undercut circumferential edge 31 and, by so forming the remaining portion of the member 24 so that it will form a sliding fit under the

edge 31, the member 24 may be rotated relative to the wheel 22. Under this arrangement the finger 26 may be moved relative to the numerical indications on the face of the wheel. Since the finger 26 is the carry over member, its relative position with respect to the numerals will determine the point at which the carry over takes place. As before stated, in ordinary practice the carry over is between 9 and 0. However, in order to carry over a half cent or more to the next cent above, it is necessary to put the carry over point between 4 and 5. Having shown a construction which will permit relative movement of the carry over member 24 to the wheel 22, it remains only to show a means for locking the member 24 into position on the wheel 22. In Figures 2 and 3, I have shown the finger 26 as being set between the numerals 4 and 5 and have shown a mechanism generally designated 32 for this purpose. Figure 5 shows an enlarged view of this mechanism. Here it can be seen that the plate 30 is formed with a radial hole 32, into which a plunger 33 slidably fits. The plunger 33 is pressed outwardly by a spring 34 and carries on its outer end a reduced pin portion 35. The pin portion 35 is adapted to fit into a small hole 36 in the member 24. With this arrangement the carry over member 24 is locked to the plate 30 and operates to transfer its accumulation to the next succeeding wheel when the indicia shows 5 or more. By carrying over between 4 and 5 instead of between 9 and 0, the sum printed by the machine will always read the next cent above when the wheel showing the fraction of cents reaches 5. In this manner, the reading of \$.495 will be automatically converted into \$.50 without any manual interference or operation. In order to convert the wheel from one to the other set-ups, it is merely necessary to depress the pin 35 so that it clears the dividing line between the members 24 and 30 and then rotate the wheel 24 until the other hole 37 comes into registration with the pin 35, whereupon the pin 35 will snap into position and the member 24 is locked in another position. The two positions represented by the holes 36 and 37 are the positions between 4 and 5 and 9 and 0 respectively on the indicator wheels.

In Figure 6, I have shown another way of applying my invention, which is equally satisfactory to that already described. Here the same wheel 22 and same gear 23 are employed and are mounted upon each other in identically the same manner as previously described. On the opposite

side, which carries the carry over wheel, there is a difference in the way the carry over wheel is mounted for relative rotation with respect to the wheel 22. In this form the plate 27 is attached to the wheel 22 by means of screws 29, while the carry over wheel 24 is rotatably mounted upon plate 27 by means of a rim 38 attached to the carry over wheel by a screw 39, said rim being undercut so as to form a sliding fit on a complementary cut on the line 40 of the member 27. A detent pin arrangement generally designated 41, similar to that designated 32 in Figure 2, is incorporated in the plate 27 and the rim 38 in the same arrangement as described in Figure 5. Either of the forms shown in Figures 5 or 6 may be used satisfactorily. There may be other forms which will serve equally as well which are not shown here but which are intended to be covered by this disclosure.

The wheel, when treated in the foregoing manner, is adaptable for either conventional accumulation or for accumulation wherein the accumulator automatically carries over half cents or more to the next cent above. The modification is simple and inexpensive and may be applied to a conventional accumulator with only slight modification. It does not interfere with the normal operation of the machine and will convert a conventional accumulator into an accumulator especially adapted for tabulating where fractions of cents appear.

I claim:

1. In a numerical accumulator, a numeral wheel, a disc having a beveled edge concentrically secured to the side of said wheel, a ring having a carry over finger thereon revolvably mounted on said disc, said ring having an internally beveled edge adapted to engage the beveled edge of said disc and retain said ring movably thereon, and means for holding said ring fixed in predetermined positions on said disc.

2. In a numerical accumulator, a numeral wheel, a disc concentrically fixed to the side of said wheel, a ring having a carry over finger thereon revolvably mounted on said disc, said ring and said disc having complementary beveled edges to form a sliding engagement therebetween, a spring pressed shouldered pin mounted in a radial hole in said disc, said ring having spaced holes smaller than said radial hole extending therethrough adapted to receive the small end of said pin and form a locking engagement between said disc and said ring.

FRANCIS GALVIN WOOD.
